SHOE SOLE CEMENTING MACHINE

Filed Sept. 22, 1930

Inventor.

William F. Green.

By W. L. Dempsey Atty.

UNITED STATES PATENT OFFICE

WILLIAM F. GREEN, OF ST. LOUIS, MISSOURI

SHOE SOLE CEMENTING MACHINE

Application filed September 22, 1930. Serial No. 483,519.

This invention relates to machines used in the manufacture of shoes and more particularly to that class of machines used for cementing the soles of shoes to the uppers.

5 The object of this invention is to provide a mobile, and resilient, foundation upon which the sole of a shoe rests so that the mobility and resiliency of the foundation will exert uniform or equal pressure on all parts 10 of the sole of the shoe.

Another object of this invention is to provide an adjustable clamping device which may be used with standard lasts of various sizes, so that the same clamping device is 15 equally effective on shoes of large or small size.

A still further object of this invention is to provide a machine of great simplicity, low cost and extreme durability.

20 Other and further objects and advantages of this invention will be disclosed in the specification, claim and drawing, in which:

Fig. 1 is a side elevation partly in section, showing a pair of shoes in position.

25 Fig. 2 is an end elevation of my invention.

Fig. 3 is an end view partly in section of a sand box.

Fig. 4 is a perspective view of the clamping device.

30 Fig. 5 is a longitudinal sectional view of the clamp shown in Fig. 4.

In the manufacture of shoes it has recently been found desirable to use cement for attaching the soles on certain classes of shoes 35 instead of using tacks or stitching. Although it has been found that the cement successfully holds the soles in place when properly applied, the difficulty has been to hold the sole in firm contact at all points.

40 The product of a day's manufacture in a modern shoe factory includes a wide variety of styles and sizes and as the styles change rapidly it would be impractical to provide a wooden or metal form to hold the soles firmly 45 in place while being cemented, since the expense involved would make the use of the press prohibitive. A large number of attempts have been made to meet this peculiar condition with more or less success and 50 failure.

The essential feature required is that the foundation or rest upon which the shoe is placed must possess a large degree of mobility and resiliency as well as firmness. The use of water has been tried but its fluidity, although non-compressible, has failed to furnish a sufficiently firm foundation as has, also, been the objection to the use of compressed air.

To overcome the objections and conditions above outlined the present invention provides an enclosure 1 covered with a suitable resilient cover 2 which may be made of rubber, fabric or other suitable material.

60 A quantity of dry sand or other finely comminuted particles adapted to conform with the contour of a body when pressed against the cover is tightly enclosed within the enclosure 1. It is evident that if pressure is exerted on any particular part of the cover, 65 in contact with the sand, it will sooner or later pack and become more stable and less yielding. Therefore, a suitable agitator 3 is provided which may consist of a worm 4, or a series of fan blades in any desired contour. 70 In order that all of the sand in the enclosure be thoroughly broken up and made homogeneous, in my preferred method two rotatable agitators 3 and 5 are provided and caused to 75 turn in unison by means of the cogs 6 and 7 80 and the crank 8.

The enclosure 1 is horizontally disposed upon the floor 10 within a frame 11, preferably made of iron and provided with screw-threaded openings 13 through which a screw 85 14, having corresponding threads, is inserted and rotated by the detachable wheel 15 and handle 16.

86 A shoe 17 is placed in position on the cover 1, utilizing the same last 18 around which the shoe was built, so that it is not necessary to have a special last for use in clamping the sole in place.

Identical clamping pieces 19 are provided, the main body portions 20 of which are adapted to be disposed in a horizontal position, from which the minor portions 21 depend at approximately a right angle, and are provided at their lower ends with a suitable cushion 22, which may be made of felt or 100

other suitable material that will not mar the finish of the leather on the toe of the shoe when placed in the position shown in Fig. 1.

The frame 11 when viewed from the end is substantially the shape of an inverted V, the side members 11 converging to a point to support the crossbeam 23. The clamping members 19 are provided with a plurality of shallow openings 24 which are adapted to receive the upper end of the threaded bolt 25 and adjustable by means of the nut 26 to different sizes of shoes. Also, on the upper or reverse side of the clamping members 19 a number of shallow openings 27 are provided for engaging the lower end of the screw member 14, the purpose of which is to permit adjustment of the screw member 14 to different sizes of shoes.

It is, therefore, obvious that when pressure is exerted by the screw member 14 on top of the clamping member 19, when properly adjusted, an even and uniform pressure will be exerted on the soles 28 of the shoes, when in position, and the compactability and mobility of the sand will cause this pressure to be equally and uniformly distributed throughout the entire area of the sole being cemented to the shoe.

Having fully described my invention, what I claim as new and useful and desire to protect by Letters Patent is:

A shoe sole cementing machine of the class described, comprising a frame having substantially V-shaped ends terminating at their lower ends in feet adapted to support said frame upon a work bench, the upper portions of said V-shaped ends being rigidly joined together by a tie-beam disposed horizontally and provided with screw-threaded openings adapted to receive a screw, a screw fitted with a detachable handwheel adapted to operatively engage said openings and exert pressure upon a clamp, a clamp having one end turned downwardly at right angles to its major axis and provided with a cushion adapted to engage the toe of a shoe and provided at its opposite end with a plurality of bores adapted to receive one end of an adjusting bolt, a bolt adapted to engage the openings in said clamp at one end and to engage a like opening in a shoe last at the other end, a threaded nut on said bolt adapted to adjust the horizontal position of said clamp, a floor affixed in said frame, a box filled with a mobile, compactible substance and having a bottom, side and end walls and a heavy flexible and resilient top, agitators journaled in said box, and means for rotating said agitators.

In testimony whereof I have hereunto affixed my signature this 12th day of August, 1930.

WILLIAM F. GREEN.
